POWER-OPERATED VIBRATING HAIR BRUSH

Monte Levin, Roslyn Heights, N.Y., assignor to Empire Brushes, Inc., Port Chester, N.Y., a corporation of New York

Filed Dec. 30, 1965, Ser. No. 385

Term of patent 14 years

(Cl. D9—2)

FIG. 1

FIG. 2

FIG. 4

FIG. 1 is a top plan view of a power-operated vibrating hair brush embodying my new design;

FIG. 2 is a side elevational view thereof;

FIG. 3 is a front elevational view thereof; and

FIG. 4 is a rear elevational view thereof.

The dominant features of my design reside in the portions shown in full lines.

I claim:

The ornamental design for a power-operated vibrating hair brush, substantially as shown and described.
